US00D758830S

(12) **United States Design Patent**
Partridge et al.

(10) **Patent No.:** **US D758,830 S**
(45) **Date of Patent:** **** Jun. 14, 2016**

(54) **LIGHTNING PROTECTION MOUNT**

(71) Applicant: **LIGHTNING PROTECTION SYSTEMS, LLC**, North Salt Lake, UT (US)

(72) Inventors: **Kirk Partridge**, Park City, UT (US); **Todd Vought**, Park City, UT (US); **Travis Vought**, Salt Lake City, UT (US)

(**) Term: **14 Years**

(21) Appl. No.: **29/525,937**

(22) Filed: **May 5, 2015**

Related U.S. Application Data

(60) Division of application No. 14/448,684, filed on Jul. 31, 2014, now Pat. No. 9,263,864, and a continuation-in-part of application No. 14/600,270, filed on Jan. 20, 2015, which is a continuation of application No. 13/676,292, filed on Nov. 14, 2012, now Pat. No. 8,950,055.
